UNITED STATES PATENT OFFICE.

BARTON E. SPERRY, OF BATAVIA, ILLINOIS.

STEAM-GENERATING STOVE.

SPECIFICATION forming part of Letters Patent No. 308,210, dated November 18, 1884.

Application filed January 14, 1884. (No model.)

To all whom it may concern:

Be it known that I, BARTON E. SPERRY, a citizen of the United States, and residing at Batavia, in the county of Kane and State of Illinois, have invented certain new and useful Improvements in Steam-Generating Stoves, which are fully set forth in the following specification, reference being had to the accompanying drawings, in which—

10 Figure 1 represents a side elevation of my improved stove; Fig. 2, a transverse sectional view taken at the line *x x*, Fig. 1; and Fig. 3, a longitudinal section taken at the line *y y*, Fig. 2, with the top of the water-reservoir 15 cut away.

15 My improvement relates to stoves for generating steam, which are especially adapted to be used for farm purposes for cooking food for cattle, and for such other purposes as steam is 20 used on farms.

25 My invention consists in the devices and combination of devices hereinafter fully described.

30 In the accompanying drawings, A represents the bottom plate of the stove, which is supported upon legs B. C are the side plates of the stove, which rest upon the bottom plate, A, and have lugs D cast upon their side to support the grate E. F is the back plate 35 of the stove, cast with an opening for the smoke-pipe G. H is the front plate, provided with a fuel-door, I, and an ash-door, J. These plates, which form the box stove, are all cast with a top horizontal rim, K, which turns inwardly and forms a support for the water-reservoir, as clearly shown in the drawings. L is 40 the bottom plate of the water-reservoir, and having downwardly-turned flanges M in its outer edge, which fit over the upper edges of 45 the stove, as shown. N is the top plate of the water-reservoir, which rests upon the bottom plate, M, and is riveted thereto by rivets O, forming a water-tight joint. P are vertical pipes extending through the bottom plate, L, 50 of the water-reservoir down into the fire-box of the stove. They are suspended from the plate L of the water-reservoir. Q are horizontal pipes connecting the pipes P, that are on one side of the stove, together. The pipes Q 55 are closed at their ends, but can be opened so as to clean out any sediment that may settle

in the pipes Q. R is a water-pipe admitting water into the water-reservoir. S are gage-cocks to show how much water there is in the water-reservoir, and they also may be used for 55 drawing hot water from the water-reservoir. T are steam-pipes through which steam may be conducted by means of hose or other convenient connections to vessels where food is steamed, to cook it. They may be provided 60 with suitable cocks, so as to take steam from only one pipe or from both at the same time, when desired. U is a safety-valve, V a weight which weights the safety-valve, and X a blow-off steam-pipe.

65 The fire-box of my stove is entirely open at the top. The steam-reservoir and the steam-pipes, as well as the water-pipes connected to the bottom of the water-reservoir, are made 70 separate and are placed upon the stove, the steam-pipes extending down into the fire-box on either side, leaving a space between them for the fuel. The water is heated rapidly in 75 the water-pipes that extend down into the fire-box, and the water in the water-reservoir becomes thereby rapidly heated.

75 The stove and the water-reservoir are made cheaply, and can be set up and put in use wherever an ordinary stove can be used. Steam can be generated very rapidly by it and used 80 by connecting the steam-pipe at the top of the water-reservoir with any ordinary vessel in which food is placed that it is desired to steam. The water-gages S are placed at different 85 heights on the water-reservoir, so that the proper quantity of water may always be kept in the reservoir. The pipes Q and P are always kept full of water, and as the water becomes heated and the steam is generated in them it rises into the water-reservoir above 90 and the colder water in that reservoir takes its place until the entire quantity of water becomes equally heated. The pipe R is used for admitting water into the reservoir, and is connected with a water-supply tank; or the 95 water may be forced in through the pipe R by any suitable means. I ordinarily conduct steam from one of the pipes T into the water-tank, and thereby force the water into the water-reservoir through the pipe R, which is connected to the water-tank by means of hose or 100 other suitable connection. The steam also

serves to partially heat the water in the water-tank.

Having thus fully described the construction and operation of my invention, what I claim as new, and desire to secure by Letters Patent, is—

1. The combination of the flat bottom plate, L, the arched top plate, N, having on its lower edges flanges parallel with the bottom plate, and bolts O, connecting the flanges to the bottom plate, substantially as and for the purpose described.

2. The combination of the top plate, N, in a water-reservoir, the bottom plate, L, provided with downwardly-turned flanges M, the water-pipes P and Q, suspended from the bottom plate, L, the inlet water-pipe R, the steam-outlet pipe or pipes T, and the open-topped stove, substantially as specified and shown. 15

BARTON E. SPERRY.
